UNITED STATES PATENT OFFICE.

EILBECK HUNTER TALIAFERRO, OF ATLANTA, GEORGIA, ASSIGNOR, BY DIRECT AND MESNE ASSIGNMENTS, OF PART TO J. B. JACKSON, T. A. WARREN, W. C. ABERNATHY, W. H. BLANTON, AND MARCELLUS B. HALLMAN, ALL OF SAME PLACE.

NURSING-CHAIR.

SPECIFICATION forming part of Letters Patent No. 355,230, dated December 28, 1883.

Application filed July 8, 1886. Serial No. 207,516. (No model.)

To all whom it may concern:

Be it known that I, EILBECK HUNTER TALIAFERRO, a citizen of the United States of America, residing at Atlanta, in the county 5 of Fulton and State of Georgia, have invented certain new and useful Improvements in Nursing-Chairs; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to an improvement in nursing-chairs; and it consists in an attaching-clamp, an adjusting-arm, and a revolving couch, and having details of construction, as hereinafter fully described.

20 In the accompanying drawings, Figure I is a perspective of the device attached to the chair. Fig. II is a detail, partly in section, showing the arrangement by which the arm is adjusted in the socket on the chair-clamp. Fig. III is a detail in section, showing the upper end of the arm, a portion of the couch, the journal on which it is pivoted, and the coil-spring.

25 In the drawings, A represents a chair of any ordinary construction. To the side of the chair is attached a screw-clamp, on the sides of which is a socket, E. In the socket on the clamp is a sleeve, F, which passes freely through it, and is held in any position in the socket E by the thumb-screw f. The standard is of such form as will bring the upper end into a position about in front of the person sitting in the chair.

30 C is a vertical socket in the upper end of the arm, to receive the journal on which the couch is fastened.

35 B is a couch of a convenient size to support a nursing-infant, and of a shape to conform nearly to that of the child's body, and also to 45 accommodate itself to that of a person sitting

in the chair—that is to say, the couch is narrowed near its ends by curving inwardly those portions of the two sides most likely to come in contact with the body of a person sitting in the chair, to make those portions 50 conform as nearly as possible thereto. The pivot b of this couch is surrounded by a spiral spring, s, which gives the couch a slight vertical elasticity, and also means of making a small adjustment vertically, the spring being about strong enough to counterbalance the 55 weight of the child.

The arm D at its lower end passes through the sleeve in the socket on the clamp H, and turns freely in it, and is provided with a 50 shoulder, G, on the lower end, which rests on the top of the sleeve and supports the arm.

The operation of this device is as follows: The person to nurse the child sits in the chair, and bringing the couch to her front 65 adjusts its height by means of the thumb-screw f, and with the child lying on the couch can nurse it either side by reversing the couch on its pivot. The couch is narrow near each end to conform to the form of the 70 person in the chair, and is concaved laterally for the purpose of comfort and greater security against falling out.

It is not my purpose to claim anything 75 shown in my application of a recent date for improvement in nursing-chairs, as this invention is composed of details not generally found in that application; but

What I claim as new, and desire to secure by Letters Patent of the United States, is— 80
1. In a couch attachment for a nursing-chair, the combination of the clamp H, having the socket E, formed integrally therewith, the sleeve F, having the thumb-screw f, the arm D, having a shoulder, G, to rest on the 85 sleeve F, the socket C, and the couch B, arranged substantially as described, and for the purpose specified.

2. The combination of the couch pivoted on the upper end of the pivoted arm B, a 90

clamp having on its side a socket and thumb-screw, with a sleeve, and an arm pivoted in said sleeve, substantially as described.

3. In a nursing-couch, the combination of
5 a pivoted arm, D, with a pivoted couch, B,
laterally concaved, and being narrowed near
the center, and also near its upper end, sub-
stantially as shown, and for the purpose speci-
fied.

In testimony whereof I affix my signature in the
presence of two witnesses.

EILBECK HUNTER TALIAFERRO.
